[57] CLAIM

The ornamental design for a trim piece for an automobile hood, substantially as shown.

DESCRIPTION

FIG. 1 is a top, front, left end perspective view of a trim piece for an automobile hood showing our new design, it being understood that the broken lines are for illustrative purposes only;

FIG. 2 is a top plan view thereof;

FIG. 3 is a rear elevational view thereof;

FIG. 4 is a bottom plan view thereof; and

FIG. 5 is an end elevational view thereof, the opposite end being a mirror image of that shown.

FIG. 1

FIG. 2

FIG. 3

FIG. 4

FIG. 5
